UNITED STATES PATENT OFFICE.

JOHN COLLINS, OF HIGHLANDVILLE, MASSACHUSETTS.

DESIGN FOR A LEGGING.

SPECIFICATION forming part of Design No. 12,656, dated January 10, 1882.

Application filed November 16, 1881. Term of patent 3½ years.

To all whom it may concern:

Be it known that I, JOHN COLLINS, a citizen of the United States, residing at Highlandville, in the county of Norfolk, State of Massachusetts, have invented a new and original Design for Leggings, of which the following is a specification, reference being had to the accompanying photographic illustration, forming part thereof.

10 The outline of the legging shown in the photograph is as usual, my invention in design being the ornamentation thereof. Near the center of the enlarged part of the legging I have knitted into the fabric a silk or other thread, 15 forming a stripe, *a*, contrasting in color with the body or ground *b* of the legging. This stripe *a* is shown as a diagonally-arranged series of stitches, 2, and above the said series a row of stitches, 3. The stripe *c* shows the ornamental stitches just the reverse of those of the stripe *a*. In the body of the legging, above and below the stripes *a* *c*, are stripes *d*, composed of a series of ornamental stitches, forming spots somewhat resembling the letter *x*, 20 each lowermost right-hand stitch in each spot (there being fourteen spots shown in the stripe *d*) being separated from the other stitches of

the spot. On the body of the legging, both above and below the stripes *d*, are stripes *e*, composed each of two courses of stitches, 5 6, 30 and four courses of ornamental stitches, 7.

I claim—

1. In a design for leggings, the two central stripes, *a* *c*, containing oppositely-inclined diagonal stitches, as shown.
2. In a legging, the two rows of diagonally-placed but oppositely-inclined stitches and the row 3 of stitches near them, as shown and described.
3. In a legging, the stripe *d*, composed of *x*-shaped spots, as shown and described.
4. In a legging, the central stripes, *a* *c*, with the stripes *d* above and below them, as shown and described.
5. In a legging, the stripes *a* *c*, *d* *d*, and *e* *e*, 45 as shown and described.

In testimony whereof I have signed my name to this specification in the presence of two subscribing witnesses.

JOHN COLLINS.
